ALLEN H. BABCOCK, OF BERKELEY, CALIFORNIA.

HEADLIGHT-DIMMER.

1,219,066.

Specification of Letters Patent. Patented Mar. 13, 1917.

Application filed March 15, 1916. Serial No. 84,268.

To all whom it may concern:

Be it known that I, ALLEN H. BABCOCK, a citizen of the United States, residing at Berkeley, in the county of Alameda and State of California, have invented certain new and useful Improvements in Headlight-Dimmers, of which the following is a specification.

My invention relates to that class of devices for relieving the glare of the headlights of vehicles, in which some form of shield is fitted to the lamp-globe or is associated therewith.

As these devices are commonly known and used in connection with automobile headlights, I shall herein mainly describe my invention in terms of such lights, though it is to be understood that my invention is equally applicable to the headlights of locomotives or to any headlights the glare of which it is desirable to relieve.

It is well known that the stray rays from automobile headlights are objectionable both to the driver of the car and also to pedestrians and to drivers of other vehicles. Various devices, known as dimmers, have been developed to remove the objectionable features of such headlights, nearly all of which when effective as dimmers, diminish materially the illuminating powers of the headlights, and, therefore, are detrimental to the safety and the convenience of the driver of the vehicle.

The object of my invention is to remove the objectionable features of such headlights, and at the same time to increase the illumination of the roadway along the path of the vehicle.

While my invention has been designed to be used in connection with the usual round bulb incandescent electric lights placed within a reflector the surface of which is substantially a paraboloid of revolution, and will be described as such, yet it may be adapted to other forms of illuminant in other forms of reflectors, as any one skilled in the art can see from the present disclosure.

The nature of my invention, together with the manner of its use and the principles upon which it is founded will be fully ascertained and understood from the following description to be read with reference to

the accompanying drawings in which is illustrated one form of its practice. 55

Figure 1 is a sectional side view of a reflector, with a lamp in the focus thereof, the lamp being in elevation with my dimming reflector member in place.

Fig. 2 is a front elevation of the lamp 60 with attached dimming reflector member.

Fig. 3 is a front elevation of the lamp with a dimming reflector member slightly modified in shape to better adapt it for certain uses. 65

1 is an electric lamp with its filament 2 wound in concentrated form and placed in a reflector 3, so that the lamp filament is in the focus of the reflector.

When the filament is caused to glow, the 70 rays of light will issue therefrom in all directions. Those rays that strike the reflector will be reflected along the axis of the reflector and substantially parallel thereto. Those rays that do not strike the reflector 75 will proceed directly from the lamp along radial lines. The direct rays that issue in a downward direction are useful because they strike and illuminate the path of the car between the car and the brilliantly illuminated area where the reflected rays are directed, and also on each side of the path of the car, which is useful in turning curves. On the other hand, the direct rays that issue in an upward direction are objectionable 80 to the driver, particularly in bad weather conditions, such as in fog or in misty weather, or when it is snowing or raining, or when dust is rising in the roadway; and they are objectionable to the drivers of other 85 vehicles and to pedestrians, because they tend to confuse the vision by opposing a bright light on a comparatively dark background.

4 is a concave spherical reflector of radius 95 substantially that of the lamp-globe 1.

The reflector 4 may be associated with the lamp-globe more or less intimately, that is to say, it may be formed with or on the globe or adherently attached thereto, or it 100 may be a separate piece, say of metal, with a highly polished inner surface. As a separate piece, it may be supported in any suitable manner. A simple and effective connection is that here shown, namely, a hole 105 5 in the lower portion, which fits over the

tip 6 of the globe, and a connection, which may be a spring 7, or other link, extending, one on each side, from the inner angle of the reflector member 4 to a band 8 upon the lamp base 9.

5 The position of the reflector member 4 is essential. It is placed over the forward upper portion of the globe 1, in such manner that none of the direct rays can emerge 10 from the headlight case in directions above the horizontal.

In this position, not only will the objectionable qualities of the direct rays, enumerated above, be removed, but also those 15 direct rays, so intercepted, will be reflected back toward and focused upon the filament 2, and then will proceed from it to the reflector 3, precisely as if they had issued in those directions initially; then they will be reflected forward along the axis, and thus 20 will strengthen the reflected beam; in other words, they will be converted from useless and objectionable rays to useful rays.

For some uses, such as on locomotive head- 25 lights, it has been found desirable to shape the reflector member 4 to intercept some of the direct rays that otherwise would emerge sidewise slightly below the horizontal. This is shown in Fig. 3 in which the sides 4' of said member are dropped slightly 30 below the horizontal plane. In all cases, however, it is best to drop the forward lower lip 4" slightly below the horizontal for two reasons; first, to use the lamp tip 35 6 to help support the dimmer, and second, because the lamp filament is not always exactly central in the lamp globe and always 40 is of appreciable size, consequently some of the direct rays may issue from below the focal point and hence tend to emerge from the headlight case in directions above the horizontal. In any case, the dimmer should 45 extend over the upper portion of the lamp globe only as far back from the front as will insure that none of the direct rays can escape around the edges of the upper periphery of the headlight case.

Dimmers made according to my above described invention have proven in practice 50 to be useful and desirable additions to the headlight equipment both on automobiles and on railway locomotives, particularly in fog. Without the dimmers, the direct rays that issue upward are reflected by the fog 55 particles and produce the effect of an opaque mass traveling ahead of the vehicle; with the dimmers, this opaque mass no longer exists, because its cause has been removed, and the driver's eye now can follow the reflected beam of light to its end. My invention 60 thus tends to promote safety.

I am aware that cups have been applied 65 to headlight lamps, as dimmers; but they are all, as far as I am aware, hemispherical or nearly so, and, therefore, they cut off

practically one-half the reflected beam. Moreover, no advantage seems consciously or designedly to have been taken of the properties of the spherical reflector to recover and make useful the direct rays so intercepted; and, furthermore, such cups are almost invariably placed on the bottom side of the lamp-globe, so that not only do they fail to remove the upward objectionable direct rays, but also they do remove 70 the downward useful direct rays. 75

In another very important respect my invention is a distinct improvement. The size of any lamp bulb is determined by the rate of heat radiation necessary to keep the lamp filament within the permissible working temperature; and inasmuch as the radiation from unit surface is sensibly constant, the surface of the bulb is a direct function of the rate of energy conversion by the lamp 80 filament. For obvious reasons, the lamp makers design the bulbs as small as is practicable. If then there is applied to the lamp bulb any device that limits the heat radiation therefrom, the temperature of the lamp 85 filament will be increased, and the lamp will deteriorate more rapidly, and its useful life will be materially diminished; also, the temperature of a part of the bulb itself will be increased, and such local heating 90 leads to failure of the glass. Evidently, then, the dimming member should be as small as possible, and it should be either transparent (which is incompatible with dimming)—or as near as possible totally reflecting. 95

Since all previous forms of cup dimmers, as far as I am aware, cover one-half, or nearly one-half of the lamp globe, and are translucent or semi-opaque, and are only incidentally partially reflecting, as any surface is more or less; and as, on the contrary, my invention covers not more than one-quarter of the lamp-bulb, and preferably as much less than one-quarter as the shape of the main reflector permits, and has its concave face made as highly polished and reflecting as is commercially practicable, the distinctive improvement in my device is apparent. 110

In using the term spherical herein as applied to the dimming reflector member, I do not confine its meaning strictly to a true sphericity, for its curvature may be of conic or other section according to the shape of the lamp-globe; and the term spherical I, therefore, use as generic to any curvature which will reflect back to the filament of the lamp. 115

I claim:—

In a headlight and in combination with its principal reflector and its focal lamp, a ray-affecting device consisting in its entirety of a spherical secondary reflector member having a full reflecting surface on 120

its concave face and an area so related to the principal reflector that none of the direct rays from the source of light to the principal reflector will be affected, said member closely covering substantially only the upper forward quadrantal section of the lamp globe and having a radius adapting it to intercept and reflect back to the principal reflector only those direct rays from the lamp which otherwise would emerge from the headlight case above the horizontal, said reflected rays being thrown back to the reflector in such directions that by the latter they will be reflected substantially parallel with its axis. 15

In testimony whereof I have signed my name to this specification in the presence of two subscribing witnesses.

ALLEN H. BABCOCK.
